CHARLES E. DENHOF, OF CLOVIS, NEW MEXICO

ELECTRIC STAMPING DEVICE

Application filed May 24, 1926. Serial No. 111,365.

This invention appertains to printing or stamping by the application of heat to the type or printing members, the device being particularly adapted for printing in gold leaf and the like on leather and similar goods.

5 The primary object of the present invention is the provision of a novel printing device embodying a hollow body having an electric heating element therein and novel means for holding the type or printing members in intimate contact with the lower face of the hollow body and novel means for facilitating the manipulation of the body.

10 A further object of the invention is the provision of a printing device embodying the hollow body containing the electric heating element and type bars extending longitudinally of the hollow body for receiving the type or other printing members and novel means for holding the type bars firmly in place so as to preclude the movement of the type or printing members.

15 A further object of the invention is the provision of an electrically heated device embodying a means for holding the type or printing members removably in place in intimate contact with the hollow body and a manipulating handle connected with the body forming a conduit for the entrance of current 20 conducting wires into the body for connection with the heating element.

25 A still further object of the invention is to provide an electrically heated printing device of the above character, which will be durable and efficient in use, one that will be simple 30 and easy to manufacture, and one which can be placed upon the market at a reasonable cost.

35 With these and other objects in view, the invention consists in the novel construction, arrangement and formation of parts, as will be hereinafter more specifically described, claimed, and illustrated in the accompanying drawings, in which drawings:

40 Figure 1 is a side elevation of the improved electric printing device, showing one of the clamping straps broken away and in section,

45 Figure 2 is a bottom plan view of the device,

Figure 3 is an end elevation of the same,

50 Figure 4 is a detail transverse section

through one corner of the device illustrating the formation of the type retaining bars and the means for holding the type retaining bars,

55 Figure 5 is a fragmentary perspective view illustrating the type retaining bars and the clamping means therefor,

Figure 6 is a side elevation of a slightly modified form for holding the type or printing members in place,

60 Figure 7 is a bottom plan view of the form shown in Figure 6,

Figure 8 is an end elevation of the same,

65 Figure 9 is a detail section through one of the type holding bars with the type in position taken on the line 9—9 of Figure 7,

Figure 10 is a detail perspective view of one of the type holding or carrying bars, and

66 Figure 11 is a detail perspective view of one piece of type.

70 Referring to the drawings in detail, where-in similar reference characters designate corresponding parts throughout the several views, the letter A generally indicates one form of the improved electric heated printing device which comprises a hollow body

75 15 preferably formed from metal. The body as shown is of a substantially rectangular configuration and includes the bottom wall 16, the side walls 17, the end walls 18 and the top wall 19. Arranged within the hollow body 15 is any preferred type of electric heating element 20 and as this heating element can be of any preferred character

80 suitable for the purpose and well known in the art, the same will not be described in detail. The top or one side wall of the body 15 can be made removable to allow the placing

85 of the heating element 20 in position and this wall can then be riveted or otherwise secured in place. The top wall 19 at the meeting

90 points of the transverse and longitudinal centers of the body is provided with a manipulating handle or hand grip 21 which can be removably or permanently secured in place.

95 This handle 21 is provided with a longitudinally extending bore for forming a conduit for the current conducting wires

99 which are connected in the ordinary manner to the terminals of the electric heating element 20.

In the form A of my invention I provide a plurality of pairs of type holding bars 23 which, as shown, extend longitudinally of the bottom wall 16 of the body. The inner faces of these pairs of the type holding bars 23 are beveled as at 24 so as to receive the wedge shaped body portion 25 of the type 26 therebetween. The type 26 can bear any desired letters, characters or insignia that may be desired to impress upon the leather goods or other articles being stamped. It is to be understood that the type is freely removable from the bars 23.

In order to hold the type bars 23 in correct position longitudinally of the bottom wall 16 of the body 15 and the type 26 in intimate contact with the body, novel clamping means 30 and 31 are provided. The clamping means 30 and 31 are located adjacent to the opposite ends of the body and each includes the transversely extending locking bars 32 which are of a substantially wedge shape in cross section for fitting in V-shaped notches 33 in the lower faces of the type bars 23 adjacent to the opposite ends thereof. The outer ends of these transversely extending bars 32 are provided with up-standing arms 34 and 35 which are adapted to engage the opposite side walls 18 of the body 15. The upper end of the arm 35 terminates in a screw threaded shank 36, while the upper end of the arm 34 is provided with a clamping arm 37 for engaging the top wall of the body. The outer end of the clamping arm 37 is provided with a suitable opening for receiving the threaded shank 36 and a wing nut 38 can be threaded on the shank 36 and the arm 35 will be raised moving the clamping arm 32 in firm contact with the type bars 23, thus forcing the broad bases of the type 25 in abutting relation to the bottom wall 16.

When it is desired to remove the type bars it is merely necessary to loosen the nut 38 so that the bars 23 can be moved transversely relative to one another so that the type can be slid from out of engagement with the bars. The new type can then be inserted between the pairs of type bars and the bars of each pair moved into contact again with the type after which the nuts can be again adjusted.

When it is desired to use the type, the current is turned on by any preferred type of switch and when the type becomes suitably heated, the gold leaf or other transparent paper is placed on the article which is to be stamped after which the stamping device is placed thereon and pressure applied thereto. The heat facilitates the application and the adherence of the gold or other transfer to the article being stamped and gives the same a desirable and pleasing appearance.

In Figures 6 to 10 inclusive I have shown

a slightly modified form of means for holding the type in position and in this form the body 15 adjacent to one end wall 18 is provided with depending ears 40 which receives a pivot pin or rod 41 which extends transversely of the bottom wall 16 of the body. Any desired number of type receiving bars 42 can be provided and one end of each bar is provided with a hinge barrel 43 for swinging movement on the hinge pin 41. Each of the type receiving bars 42 is provided with a longitudinally extending slot 44 for the reception of the type which is shown in detail in Figure 11 of the drawings. The type is indicated by the reference character 45 and as shown, the opposite sides thereof are provided with guideways 46 for the reception of guide legs 47 defined by the slots 44 in the bar 42. The type when viewed in end elevation is of a substantially I-shape. In order to hold the bars 42 in correct position and the type in intimate contact with the body 15 the opposite end of the body from the ears 41 is provided with a swinging yoke 48. This yoke 48 is in the nature of a closed loop and includes a bottom clamping bar 49, a parallel top bar 50 and connecting side bars 51. The side bars 51 are provided with vertical slots 52 for the reception of pivot pins 53 carried by the side walls 17 of the body. The top bar 50 is provided with threaded thumb screws 54 for impinging against the top wall of the body and it is obvious that by tightening up on the screws 54 that the bottom clamping bar 49 will swing the type bars 42 toward the bottom wall 16 of the body and thus urge and hold the type 45 in contact with the lower wall 16 of the body. When it is desired to remove the type from the type bars it is merely necessary to loosen the screws 54 and swing the clamp 48 outwardly on the pins 53 which will allow swinging movement of the type bars 42 on the pivot pin 41 and the removing of the type therefrom.

From the foregoing description, it can be seen that I have provided a novel stamping device which is of the electric heated type embodying the novel means for holding the type in firm contact with the heated body.

Changes in details may be made without departing from the spirit or scope of this invention, but what I claim as new is:

1. A printing and stamping device comprising a body, type carriers, and means for holding the type carriers against one face of the body for bodily adjustment with respect to each other in a plane parallel to said face and adapted to clamp the type carriers in adjusted position against said face.

2. A printing and stamping device comprising a body, means carried by the body and adjustable toward and away from one face thereof and type carriers positioned between said means and face and associated with said means for bodily adjustment with respect to

each other in a plane parallel to said face when said means is adjusted away from said face.

3. A printing and stamping device comprising a hollow body, electric heating elements in said body, pairs of longitudinally extending type holding bars on the lower face of the body, the inner faces of each bar of the pairs of bars having beveled faces, the type having wedge shaped bodies fitted between the faces, the bars also having adjacent to the outer ends thereof V-shaped notches in their lower faces, a transversely extending clamping bar seated in said notches, and means surrounding the body for moving the clamping bars toward the body, and the type in intimate contact with the body.

4. A printing and stamping device comprising a body, a type carrier arranged at the lower face of the body and provided on its underside adjacent its ends with transverse notches, transversely extending clamping bars removably seated in said notches, upstanding arms secured to the ends of the clamping bars and arranged in contact with the sides of the body, certain of said arms being provided at their upper ends with screw threaded shanks, clamping arms arranged in contact with the upper side of the body and connected to the upper ends of the other of said upstanding arms, the clamping arms being provided with openings for the reception of said shanks and nuts engaged with the shanks for contacting with the upper sides of the clamping arms.

In testimony whereof I affix my signature.
CHARLES E. DENHOF.
